 a corporation of Indiana

Application October 18, 1935, Serial No. 45,571

2 Claims. (Cl. 188—152)

This invention relates to brakes, and is illustrated as embodied in an internal expanding brake for an automobile. An object of the invention is to provide a simple and powerful brake 5 in which both shoes are fully effective in both directions of rotation of the brake drum, i. e., in both forward and reverse braking.

In one desirable arrangement, the shoes are arranged between two anchors across the brake 10 from each other, so that they are individually shiftable to anchor at either end according to the direction of drum rotation, and are actuated by floating wedges carried by a pair of levers spread apart by pressure-balancing means, 15 preferably a cylinder containing a pair of pistons connected respectively to the levers.

The above and other objects and features of the invention, including various novel combinations of parts and desirable particular constructions, will be apparent from the following 20 description of the illustrative embodiment shown in the accompanying drawing, in which:

Figure 1 is a vertical section through the brake, just inside the head of the brake drum, showing 25 the brake shoes in side elevation;

Figure 2 is a partial section through the brake, on the line 2—2 of Figure 1; and

Figure 3 is a partial section on the line 3—3 of Figure 1.

The illustrated brake includes a rotatable drum 10, at the open side of which is arranged a support such as a backing plate 12, shown as having spot-welded or otherwise secured thereto, across the drum from each other, a pair of 35 angle-shaped steel stampings 14 and 16, which project into the drum immediately inside the braking flange thereof to form anchors taking the braking torque.

Between these anchors are arranged two T- 40 section shoes 18 and 20, the webs of which are engageable with the anchors at their opposite ends, and which webs project past said anchors and radially inside thereof as thrust portions carrying spindles 22 on which pairs of thrust 45 rollers 24 are mounted on opposite sides of the webs. The shoes are normally held in retracted position, against the anchors, by means such as return springs 26 tensioned between the shoes.

The brake is applied by novel means shown as 50 including two levers 28 and 30, pivoted on the

backing plate inside the drum and movable in a plane beside and paralleling the backing plate. These levers have floatingly connected thereto, for example by links 32, wedges 34 acting on the rollers 24. As shown in Figure 2, the wedges 5 may have positioning ribs 36 projecting between the rollers 24.

The levers 28 and 30 are applied by pressure-balancing means, preferably of the hydraulic type. I prefer to utilize a double-ended hydraulic cylinder 38 mounted on the backing plate inside the drum approximately opposite the center of the shoe 18, and containing two pistons 40 and 42 connected by means such as piston rods or links 44 respectively to the levers 28 15 and 30.

While one illustrative embodiment has been described in detail, it is not my intention to limit the scope of my invention to that particular embodiment, or otherwise than by the terms of 20 the appended claims.

I claim:

1. A brake comprising a drum having a backing plate at its open side, anchors projecting from said plate adjacent the braking surface of 25 the drum and arranged across the drum from each other, shoes arranged within the drum and each engageable with said anchors at its opposite ends, a pair of levers fulcrumed on the backing plate across the drum from each other 30 and each carrying an outwardly movable floating wedge engageable with the ends of both shoes, and pressure-balancing means acting with substantially equal force on said levers.

2. A brake comprising a drum having a backing plate at its open side, anchors projecting from said plate adjacent the braking surface of the drum and arranged across the drum from each other, shoes arranged within the drum and each engageable with said anchors at its opposite ends, 40 a pair of levers fulcrumed on the backing plate across the drum from each other inside of the drum and each carrying an outwardly movable floating wedge engageable with the ends of both shoes, a double-ended cylinder mounted inside 45 the drum on said backing plate adjacent the central portion of one shoe, and pistons in said cylinder connected respectively to said levers.
